UNITED STATES PATENT OFFICE

126,213

DESIGN FOR A LIQUID SPRAYER

John F. Schylander, Chicago, Ill.

Application July 11, 1940, Serial No. 93,570

Term of patent 7 years

To all whom it may concern:

Be it known that I, John F. Schylander, a citizen of the United States, residing at Chicago, in the county of Cook and State of Illinois, have invented a new, original, and ornamental Design for a Liquid Sprayer, of which the following is a specification, reference being had to the accompanying drawing, forming a part thereof.

Referring to the drawing:

Fig. 1 is a side elevational view of a liquid sprayer showing my novel design;

Fig. 2 is a sectional view thereof on a slightly

enlarged scale, taken substantially on the line 2—2 of Fig. 1; and

Fig. 3 is a bottom plan view on a slightly enlarged scale of the valve liquid outlet tube shown in full lines in Fig. 1.

The dominant features of the design reside in the portions shown in full lines.

I claim:

The ornamental design for a liquid sprayer, as shown and described.

JOHN F. SCHYLANDER.
